DISPLAY RACK

Max J. Kelling, Wilmette, Ill.

Application October 22, 1954, Serial No. 32,766

Term of patent 14 years

(Cl. D80—10)

To all whom it may concern:

Be it known that I, Max J. Kelling, a citizen of the United States, residing at Wilmette, county of Cook and State of Illinois, have invented a new original, and ornamental Design for a Display Rack, of which the following is a specification, reference being had to the accompanying drawings, which form a part thereof.

The figure is a front perspective view of a display rack showing my new design.

I claim:

The ornamental design for a display rack, as shown.
